UNITED STATES PATENT OFFICE

93,834

DESIGN FOR A SHOE

Vergil C. Lipscomb, St. Louis, Mo., assignor to Wohl Shoe Company, St. Louis, Mo., a corporation

Application July 30, 1934, Serial No. 52,746

Term of patent 3½ years

To all whom it may concern:

Be it known that I, VERGIL C. LIPSCOMB, a citizen of the United States and a resident of the city of St. Louis, in the State of Missouri, have invented a new, original, and ornamental Design for Shoes, of which the following is a specification, reference being had to the accompanying drawing, forming a part thereof:

I claim:

The ornamental design for a shoe, as shown.

VERGIL C. LIPSCOMB.
